IGNITION APPARATUS

Reginald W. Beckett, Rocky River, Ohio, assignor
to The Cleveland Steel Products Corporation,
Cleveland, Ohio, a corporation of Ohio

Application April 21, 1932, Serial No. 606,713

6 Claims. (Cl. 175—115)

This invention relates to ignition devices for liquid fuel burning apparatus, and particularly to such devices wherein an electric spark is caused to pass between a pair of spaced electrodes to ignite the fuel.

There is one serious disadvantage in the use of electric spark ignition devices for liquid fuel burning apparatus, such as oil burners, and that disadvantage is that frequently deposits of carbon accumulate between the spark electrodes of the ignition device while the apparatus is in operation. Such carbon deposits may short circuit the ignition device, and frequently result in disastrous explosions, due to the fact that when there is a demand for the burner to operate, the burner will discharge the fuel which may vaporize to such an extent prior to ignition that when the carbon deposit is broken, such as by the weight of fuel deposited on the same, and the ignition device does function, an explosion will occur.

One of the objects of the present invention is to provide an ignition device of the spark type wherein the above disadvantage will be overcome.

Another object is to provide a spark ignition device for liquid fuel burning apparatus of such new and improved construction that the spark electrodes are freed from short circuiting deposits at the instant that there is a demand for a spark to be passed therebetween.

Another object is to provide a spark ignition device for oil burning apparatus wherein suitable means is bodily moved between the electrodes at the instant a demand for an initial spark is created.

A further object is to provide a spark ignition device for oil burning apparatus with an automatically controlled means for quickly freeing the electrodes of objectionable shortcircuiting carbon deposits at the time a demand for ignition is created.

With the above and other objects in view, which will be apparent from the following detailed description and the accompanying drawings, the present invention consists in certain features of construction and combinations of parts which will be readily understood by those skilled in the art to which the invention appertains.

In the drawings which illustrate suitable embodiments of the present invention for oil burning apparatus of the so-called rotary and gun or jet types,

Figure 1 is a side elevation of a spark ignition

device suitable for rotary oil burners wherein the fuel is ignited at a distance from a distributor, portions of the hearth element being broken away and shown in section;

Fig. 2 is a plan view of the device shown in Fig. 1;

Fig. 3 is a rear elevation of the device shown in Fig. 1;

Fig. 4 is a section taken approximately on the line 4—4 of Fig. 3, showing the actuator in detail;

Fig. 5 is a section taken on line 5—5 of Fig. 4;

Fig. 6 is an enlarged section taken on line 6—6 of Fig. 3;

Fig. 7 is a plan view of a modified construction suitable for a rotary type oil burner;

Fig. 8 is a side elevation of the modified device shown in Fig. 7;

Fig. 9 is a section taken approximately on line 9—9 of Fig. 8;

Fig. 10 is a plan view of a portion of an oil burner of the gun type, a portion of the housing being broken away to show the ignition device;

Fig. 11 is a side elevation of the apparatus illustrated in Fig. 10, the housing being removed and the actuator shown above the apparatus;

Fig. 12 is an end elevation of the device shown in Fig. 10; and

Fig. 13 is an enlarged side elevation of the ignition device shown in Fig. 11.

Referring to the accompanying drawings, in which like numerals refer to like parts throughout the several views, the ignition apparatus shown in Figs. 1 to 6, inclusive, is particularly adapted for oil burning furnaces of the type wherein the fuel is distributed horizontally from a centrifugal distributor to impinge against a substantially continuous refractory hearth element extending around the fire box of the furnace adjacent the furnace wall, and wherein the fuel is ignited at this hearth element.

The ignition device here shown in Figs. 1 to 6 is incorporated in one of the segments 1 that comprise the hearth element. The particular segment shown in Fig. 1 is of a stepped construction having a groove 2 formed at the inner side of the first step 3 and at the bottom of the fuel impact wall 4, the segment being provided with an inwardly extending portion 5 which assists in supporting a part of the ignition device.

The upper step 6 of the element 1 is recessed and provided with an embedded electrical conductor 7, such as a carbon block or the like, which block rests in the recess in a manner to be flush with the impact wall 4 so that it may form one

of the ignition electrodes. This block 7 of conducting material is connected with a conductor rod 8 that extends up through the bottom of the segment 1 and which is surrounded by an insulator 9 that is carried by the segment 1.

The other electrode comprises a suitable conductor 10 which may be in the form of a flat metal strip arranged to extend over the first step 3 and the groove 2 in spaced relation to the conductor 7 to provide a spark gap therebetween. The flat strip comprising the conductor 10 is attached to the upper end of a conductor rod 11 that extends through the extending portion 5 of the segment 1 and which is enclosed within a suitable insulating tube 12.

The two conductor rods 8 and 11 are connected with a suitable source of electrical energy which is controlled to produce a spark between the electrodes when a demand for ignition is created, such as by the functioning of a room thermostat which also causes the operation of the fuel distributing unit.

As previously stated, a deposit of carbon may accumulate during the operation of the oil burner between the two electrodes 7 and 10 to an extent sufficient to short-circuit the same, with the result that an explosion may occur due to the failure of the ignition device to properly function at the time a demand for ignition is created. In other words, the fuel may become vaporized during the initial starting period and then exploded by a delayed spark which may occur through breakage of the carbon deposit due to the weight of the fuel that may accumulate thereon after the fuel distributor is set in operation.

There is shown in Figs. 1 and 9 certain new and novel devices which will function instantly at the time a demand for ignition is created and break away any objectionable carbon deposit that may have caused the electrodes to short circuit.

Referring to Figs. 1 to 6, this last mentioned device takes the form of a swinging arm 13 which is mounted upon the upper end of a pivot bar 14 that extends through a suitable opening formed in the extending portion 5 of the refractory element 1, as more clearly shown in Fig. 6. This arm 13 is shaped to have a stepped portion 16 spaced above the first step 3 of the element 1 and with an upright portion 17 having a curved outer face 18 conforming in shape to the fuel impact wall 4. The arm 13 is movable in such a manner that the upright portion thereof will swing between the electrodes 7 and 10 to just clear the same and rupture any accumulated carbon deposit that may have accumulated between these electrodes. This movement takes place at the instant a demand for ignition is created, and the arm will move from the position shown in solid outline to the position shown in broken outline illustrated in Fig. 2, the arm remaining in the actuated position shown in dotted outline until the ignition period is over, at which time it will automatically move back to its normal inoperative position.

The arm 13 is actuated in the form here shown by means of an electromagnet device 19 which, although not shown here, is suitably controlled by the mechanism which controls the operation of the electrodes, that is, the mechanism which starts the sparking at the beginning of the ignition period and stops the sparking of the electrodes at the termination of the ignition period.

The electromagnet device 19 comprises, as shown in Fig. 4, a cup-shaped housing 20 secured to a supporting bracket 21 that is mounted on the

under side of the refractory element 1. This housing 20 carries a coaxial pin 22, the portion of the pin lying within the housing being circular and provided with a transverse slot 23, which circular portion receives a shading core 24 having a transverse end portion 25 fitting within the slot 23. The annular winding 26 is mounted on a spool 27 which surrounds the core 24 and the armature 28 is telescoped within the core 24. This armature is provided with a coaxial bore 29 which receives a coil spring 30, one end of the spring 30 being seated against the pin 22 and the other end being seated against the bottom of the bore 29.

The armature 28 is arranged to directly actuate the actuator or pivot bar 14 of the swinging arm 13 through an annular groove 31 which receives a lip portion 32 that is formed on the pivot bar 14, as shown in Figs. 3 and 4. The groove 31 and lip portion 32 are so arranged that during movement of the armature 28 the pivot bar 14 will be rotated to swing the arm 13.

The operation of the device just described is relatively simple and is as follows. When the oil burner apparatus is inoperative the current to the ignition device is, of course, shut off, but at the instant there is a demand for operation of the apparatus, the ignition circuit, as in conventional constructions, is closed substantially simultaneously with the start of operation of the fuel distributor, and furthermore the control apparatus is suitably arranged to instantly close the circuit for the electromagnet device 19, with the result that at the initial passing of sparks across the spark gap between the electrodes, the swinging arm 13 immediately swings between the electrodes and breaks away any carbon deposit that may have accumulated between the electrodes. The spring 30 resists this movement so that immediately at the termination of the ignition period through the operation of a time limit switch which opens the ignition and electromagnetic circuits, the spring 30 will cause the armature 28 to move to its normal position and thereby move the swinging arm 13 to its normal inoperative position.

In the construction shown in Figs. 7, 8 and 9, the device for breaking away any accumulated carbon deposits between the electrodes 7 and 10 is arranged to have a reciprocatory movement rather than a swinging movement. This device comprises an angle-shaped finger 40 of suitable metal mounted upon the end of a vertically reciprocable rod 41, the rod 41 being mounted on a laminated armature 42 arranged below the hearth segment 1. The armature 42 is influenced in its operation by a suitable electromagnet 43. Any suitable means may be provided for actuating the finger 40 and in this construction the finger can be moved upwardly to rupture any accumulated carbon deposit between the electrodes and may then be lowered to its normal position.

In Figures 10 to 13 of the drawings there is shown one type of gun type oil burning apparatus, wherein fuel is forced through a nozzle 50 that is mounted on the end of a pressure conduit 51 which is positioned within a relatively large housing 52. Air under pressure is forced through the housing 52. In this type of apparatus two spaced electrodes 53 are employed to terminate just above the opening 54 in the nozzle 50. Various types of electrodes may be used and they may be arranged in many different manners. In any event, the electrodes are spaced apart and are arranged near the opening in the discharge nozzle 75

zle. As shown in Figs. 10 to 13 the present invention may take the form of the circular element 55 circumscribing the nozzle 50 and pivoted at a point below the nozzle so that it may bodily swing between the nozzle and the electrodes, the element 55 being formed with a projecting portion 56 arranged during swinging movement of the element 55 to pass directly between the electrodes 53 in order to rupture any carbon deposit that may have accumulated therebetween.

The element 55 may be connected by an actuator rod 57 to a pivoted lever 58 which may extend through the housing 52 and be actuated directly by an electromagnet device 59 such as the device previously described in detail and which, if desired, may be mounted externally of the housing 52, as shown.

It is obvious that many different arrangements of electrodes and carbon deposit rupturing devices may be employed with respect to ignition devices for both rotary or gun type liquid fuel burning apparatus, and further to a third type of apparatus commonly called a pot type apparatus. In each instance, however, the present invention includes a pair of spaced electrodes for igniting fuel, a means arranged to pass bodily between such electrodes and a suitable apparatus, such as an electromagnet device for actuating that means in the manner described.

The apparatus of the present invention is simple in form and can be economically manufactured, yet it provides an extremely efficient safeguard for spark ignition devices used in connection with oil burning apparatus of any type, in that it will instantly break carbon deposits away from the ignition electrodes at the instant there is a demand for ignition.

Furthermore, it is to be understood that various changes may be made in the details of construction and arrangement of the several parts without departing from the spirit of my invention, and it is to be understood that my invention is limited only in accordance with the scope of the appended claims.

What I claim is:

1. In a spark ignition device for liquid fuel burning apparatus, a pair of spaced stationary electrodes, a pivotally supported shaft, an arm secured to said shaft and having a portion thereon movable directly between said electrodes upon pivotal movement of said shaft, an electromagnetic device having an annular energizing winding and a coaxial armature, said armature being connected with said shaft to rotate said shaft in one direction upon energization of said electromagnetic means, and spring means for resisting such movement and for pivoting said shaft to normal position.

2. In a spark ignition device for liquid fuel burning apparatus, a hearth segment having an upstanding portion provided with a fuel impact wall, an electrode embedded in said segment and having an electrode portion substantially flush with said impact wall, a second electrode spaced from the electrode portion of said first electrode to provide a spark gap therebetween, means movably supported by said segment to move through the spark gap between said electrodes to rupture any deposit that may have accumulated in said spark gap, and electromagnetic means for actuating said means.

3. In a spark ignition device for liquid fuel burning apparatus, a hearth segment having an upstanding portion provided with a fuel impact wall, an electrode embedded in said segment and having an electrode portion substantially flush with said impact wall, a second electrode spaced from the electrode portion of said first electrode to provide a spark gap therebetween, means movably supported by said segment to move through the spark gap between said electrodes to rupture any deposit that may have accumulated in said spark gap, and electromagnetic means for actuating said means, said first means having a face portion conforming in general shape to the shape of said impact wall.

4. In a spark ignition device for liquid fuel burning apparatus, a hearth segment having an upstanding portion provided with a fuel impact wall, an electrode embedded in said segment and having an electrode portion substantially flush with said impact wall, a second electrode spaced from the electrode portion of said first electrode to provide a spark gap therebetween, a pivotal shaft extending through said segment, an arm secured to said shaft and having a portion extending upwardly therefrom to pass between said electrodes upon pivotal movement of said shaft, and an electromagnetic means for causing pivotal movement of said shaft.

5. In a spark ignition device for liquid fuel burning apparatus, a hearth segment having an upstanding portion provided with a fuel impact wall, an electrode embedded in said segment and having an electrode portion substantially flush with said impact wall, a second electrode spaced from the electrode portion of said first electrode to provide a spark gap therebetween, a pivotal shaft extending through said segment, an arm secured to said shaft and having a portion extending upwardly therefrom to pass between said electrodes upon pivotal movement of said shaft, electromagnetic means having an armature associated with said shaft to pivot said shaft in one direction upon energization of said electromagnetic means, and spring means for resisting such movement and for pivoting said shaft to normal position.

6. In a spark ignition device for liquid fuel burning apparatus, a pair of spaced stationary electrodes, a pivotally supported shaft, an arm secured to said shaft and having a portion thereon movable directly between said electrodes upon pivotal movement of said shaft, an electromagnetic device having an annular energizing winding and a coaxial armature, said armature having a recess therein and said shaft having a lip thereon extending into said recess whereby said armature upon energization of said winding may rotate said shaft in one direction, and spring means resiliently acting in opposition to said armature to rotate said shaft in the opposite direction upon de-energization of said winding to thereby return said shaft and attached arm to normal inoperative position.

REGINALD W. BECKETT.
